(57) **CLAIM**

The ornamental design for a coolant valve, as shown and described.

DESCRIPTION

FIG. 1 is a front view of a coolant valve an according to the present application;

FIG. 2 is a rear view of the coolant valve according to the present application;

FIG. 3 is a left view of the coolant valve according to the present application;

FIG. 4 is a right view of the coolant valve according to the present application;

FIG. 5 is a top view of the coolant valve according to the present application;

FIG. 6 is a bottom view of the coolant valve system according to the present application; and,

FIG. 7 is a perspective view of the coolant valve according to the present application.

The broken lines depict parts of the coolant valve that form no part of the claimed design.
